Atty.

United States Patent Office.

LOUIS C. A. SCHMIDT, OF TIFFIN, OHIO.

Letters Patent No. 103,784, dated May 31, 1870.

IMPROVEMENT IN FLOUR-BOLTING APPARATUS.

The Schedule referred to in these Letters Patent and making part of the same

To all whom it may concern:

Be it known that I, LOUIS C. A. SCHMIDT, of Tiffin, in the county of Seneca and in the State of Ohio, have invented certain new and useful Improvements in Flour-bolting Apparatus; and do hereby declare that the following is a full, clear, and exact description thereof, reference being had to the accompanying drawing and to the letters of reference marked thereon making a part of this specification.

The nature of my invention consists in the construction and arrangement of a "flour-bolting apparatus," as will be hereinafter more fully set forth.

In order to enable others skilled in the art to which my invention appertains to make and use the same, I will now proceed to describe its construction and operation, referring to the annexed drawing, in which—

Figure 1 is a longitudinal vertical section, and

Figure 2 is a transverse vertical section of my bolting apparatus.

A represents a box, of suitable dimensions, in which the bolt B is placed.

The bolt is made in any of the known and usual ways, and its shaft, C, has a stationary bearing in the front end of the box, while the other end of the shaft passes through a vertical slot in the rear end of the box, and is, outside of the box, provided with a cog-wheel, D, or other suitable gearing, to be connected with the mechanism for rotating the bolt.

In the box-lid E, at the rear end, is a hopper, G, which comes directly over a conductor, H, in the box,

said conductor leading into the bolt, and its mouth surrounded by the head I, which is stationary on the inside of the bolt, the bolt revolving around the same.

By this arrangement the bran is kept from passing out at the end, and, at the same time, creating a breeze to cool the flour.

On the upper end of the bolt-shaft C is a toothed wheel, J, which bears on an inclined plane, K, within the box at the rear end. This wheel is so constructed that, when the bolt revolves, it drops from one-half to an inch, shaking and jarring the bolt, so that all the flour may pass out and drop into the meal-chute, and, at the same time, cooling the flour.

Having thus fully described my invention,

What I claim as new, and desire to secure by Letters Patent, is—

1. The stationary head I, surrounding the mouth of the conductor H, and placed within the end of the bolt, substantially as and for the purposes herein set forth.

2. The arrangement of the bolt B, shaft C, head I, conductor H, toothed wheel J, and inclined plane K, all substantially as and for the purposes herein set forth.

In testimony that I claim the foregoing, I have hereunto set my hand this 14th day of March, 1870.

LOUIS C. A. SCHMIDT.
